UNITED STATES PATENT OFFICE

96,518

DESIGN FOR A COMBINED WRITING AND TYPEWRITING DESK

Milton S. Stevenson, Larchmont, N. Y.

Application May 15, 1935, Serial No. 56,844

Term of patent 7 years

To all whom it may concern:

Be it known that I, Milton S. Stevenson, a citizen of the United States, residing at Larchmont, in the county of Westchester and State of New York, have invented a new, original, and ornamental Design for a Combined Writing and Type-writing Desk, of which the following is a specification, reference being had to the accompanying drawing, forming part thereof.

Fig. 1 shows my new design for the combined writing and typewriting desk in perspective, with

the cover member in vertical position, for use as a typewriting desk.

Fig. 2 shows my new design for the combined writing and typewriting desk in perspective, with the cover member in horizontal position for use as a writing desk.

I claim:

The ornamental design for a combined writing and typewriting desk, as shown and described.

MILTON S. STEVENSON.
